UNITED STATES PATENT OFFICE.

NORVAL E. WILSON AND WILLIAM G. WILSON, OF HARTFORD, CONNECTICUT.

PEDAL ATTACHMENT FOR PIANOS.

SPECIFICATION forming part of Letters Patent No. 366,285, dated July 12, 1887.

Application filed April 9, 1885. Serial No. 161,648. (No model.)

To all whom it may concern:

Be it known that we, NORVAL E. WILSON and WILLIAM G. WILSON, both of Hartford, in the county of Hartford and State of Connecticut, have invented certain new and useful Improvements in Pedal Attachments for Pianos, of which the following is a description, reference being had to the accompanying drawings, where—

10 Figure 1 is a plan view of a device embodying our invention. Fig. 2 is a side view of the same. Fig. 3 is a view in vertical section of a part of the device on plane denoted by line *x x* of Fig. 1.

15 The object of our invention is to provide a simple and convenient means of enabling a child to use the pedals of a piano; and it consists in the combination of a suitable support, as a stool, bearing a set of pedals having each 20 a connected block or like means of connecting the removable pedals with the pedals of the instrument, and in certain details of construction of the device, as more particularly herein-after described.

25 In the accompanying drawings, the letter *a* denotes the pedals of a piano, which in the drawings are shown as supported in the base of the lyre *b* in the usual manner.

The letter *c* denotes a support for the supplemental pedals *d*, which in the form shown 30 consists of a stool, *c*, bearing along its upper surface, and near the front edge of the stool, a rail, *f*, dovetailed on and movable along which are the pedal-blocks *g*. These blocks are held

35 in any desired part of their path by means of the clamp-screw *h*, borne in threaded sockets in the blocks and adapted to be forced against the upper side of the rail. Each supplemental pedal is pivoted to the upper part of a pedal-block, and also to a plunger, *i*, that passes 40 down through the slot *e'* in the top of the stool, so as to rest upon the top of the pedal *a* when the stool is in the proper position for use. The adjustable arm *k* is attached to the

45 under side of the stool by means of the bolt *l* and guide-pins *m*, and this arm projects beyond the front edge of the stool and underneath the bottom of the lyre *b*, as illustrated in Fig. 2.

50 In order to use our device, the front edge of

the stool *c* is placed against the base of the lyre *b*, the arm *k* thrust underneath the lyre, and the plungers *i* resting each upon a pedal, the pedal-blocks being adjusted so as to cause the plunger of each supplemental pedal to 55 rest directly on each of the main pedals of the piano. The grasp of the arm *k* upon the under side of the lyre may be adjusted by means of the butterfly-nut *l'* on the bolt *l*.

The stool affords a rest for the heel of the 60 player, and the supplemental pedals are used exactly as are the pedals of the piano proper.

The rods or plungers *i* may be made in sections, so that their length may be adjusted to conform to the height of pedals of different 65 musical instruments, which vary considerably, and to support the pedals *d* in proper position for use—that is, about level.

In order that the plunger may bear directly on the pedal *a*, the pedal *d* is provided with 70 an ear having a slot through which a pin in the plunger is passed, so that, notwithstanding the pedal *d* moves in an arc of a circle, the plunger *i* will move in a right line.

As the arm *k* is secured to the stool at about 75 the same vertical plane with the plungers, great stability is secured, and the use of our device will not be so liable to injure or break the lyre as devices heretofore employed.

We are aware of the pedal attachment patent 80 by W. Winter, December 11, 1883, No. 290,163, and therefore do not claim the construction he shows; but

We claim as our invention—

The herein-described improved pedal attachment, consisting of the stool *c*, the pedal-blocks *g*, adjustable thereon transversely with respect to the lyre, pedals *d*, pivoted to said blocks, a slot, *e'*, in said stool, a plunger, *i*, movable vertically through said slot, having 90 a pin-and-slot connection with the pedals *d*, to bear directly on the pedals of the instrument, and the arm *k*, secured to the under side of the stool and adjustable vertically, substantially as shown.

NORVAL E. WILSON.

WILLIAM G. WILSON.
